UNITED STATES PATENT OFFICE.

WILLIAM G. JOHNSON, OF MILFORD, MASSACHUSETTS.

BOWLING-BALL CLEANER.

Application filed April 20, 1928. Serial No. 271,594.

The present invention relates to a device for bowling balls as they move along the runway.

The object of the invention is to provide a device of this nature which is exceedingly simple in its construction, easy to attach to and detach from the runway, inexpensive to manufacture, strong and durable, and thoroughly efficient and reliable in use.

With the above and numerous other objects in view as will appear as the description proceeds, the invention resides in certain novel features of construction, and in the combination and arrangement of parts as will be hereinafter more fully described and claimed.

In the drawing:

Figure 1 is a fragmentary side elevation of the runway with my improved device mounted thereon;

Figure 2 is a top plan view thereof, and

Figure 3 is a transverse vertical section substantially on the line 3—3 of Figure 2.

Referring to the drawing in detail it will be seen that the numeral 5 denotes a conventional bowling ball runway supported adjacent the bowler's end by uprights 5 in the usual well known manner. Bracket plates 7 are secured to two adjacent uprights 6 one on each side thereof and extend up alongside the runway 5. The plates may be attached by screws 8 or in any other preferred manner.

Each plate is provided with a pair of vertically aligned sleeves 9 with set screws 10 set therethrough. The frame comprises a U-shaped body disposed in a horizontal plane and having its legs merging at their terminal to outwardly and horizontally directed extensions 11 which in turn merges into downwardly disposed extensions 12 to be received within the sleeves 9 and locked in place by the set screws 10. Elongated brush heads 14 are provided with eyes 15 engaged on the legs of the U-shaped body 16 of the frame.

These heads have downwardly projecting bristles 17 of suitable material. Obviously the brushes thus mounted may be raised or lowered and as the bowling balls pass thereby said bowling balls will be thoroughly dusted and cleaned. It will be seen that the device is exceedingly simple and may be

manufactured in a strong and durable manner at a relatively low cost and may be attached to the runway without alterations after having been attached the same is easily removed for cleaning or replacing.

It is thought that the construction, utility and advantages of the invention will now be quite apparent to those skilled in this art without a more detailed description thereof. The present embodiment of the invention has been disclosed in detail merely by way of example since in actual practice it attains the features of advantage enumerated as desirable in the statement of the invention and the above description. It will be apparent that changes in details of construction, and in the combination and arrangement of parts may be resorted to without departing from the spirit or scope of the invention as hereinafter claimed or sacrificing any of its advantages.

Having thus described my invention, what I claim as new is:

1. A device of the class described comprising a frame formed with a U-shaped body the terminals of the legs of which merge into outwardly disposed extensions which in turn merge into downward extensions, and elongated brushes secured to the legs of the U-shaped body.

2. A device of the class described comprising a frame formed with a U-shaped body the terminals of the legs of which merge into outwardly disposed extensions which in turn merge into downward extensions, elongated brushes secured to the legs of the U-shaped body, each brush comprising a head with eyes thereon receiving the respective legs and bristles extending from the head.

3. A device of the class described comprising a frame formed with a U-shaped body the terminals of the legs of which merge into outwardly disposed extensions which in turn merge into downward extensions, elongated brushes secured to the legs of the U-shaped body, a pair of plate brackets, means for securing the brackets to the sides of a bowling ball runway, the brackets being provided with sleeves to receive the last mentioned extensions and set screws engaged to hold the frame in different adjusted positions.

In testimony whereof I affix my signature.

WILLIAM G. JOHNSON.
